UNITED STATES PATENT OFFICE.

SETH R. SWAIN, OF DENVER, COLORADO.

HYDRAULIC CLASSIFIER FOR ORES.

No. 866,536.

Specification of Letters Patent.

Patented Sept. 17, 1907.

Application filed November 26, 1906. Serial No. 345,180.

To all whom it may concern:

Be it known that I, SETH R. SWAIN, a citizen of the United States, residing at Denver, in the county of Denver and State of Colorado, have invented certain 5 new and useful Improvements in Hydraulic Classifiers for Ores, of which the following is a specification.

My invention relates to an improvement in hydraulic classifiers for ores and in the method of treatment.

Although the principle of hydraulic classification of 10 ores is pretty generally acknowledged as being the most economical, still the results obtained in its achievement have generally been unsatisfactory and the reason is probably due to the comparatively little study which is given the subject, for when a hydraulic classification is desired, a device has generally been installed which has been closely copied from some other in use at some plant where conditions and ore 15 may have been entirely different. In some instances where this has been done, the classifier may have given 20 good results, but when ores, whose components are close in specific gravities, are to be handled, the utmost care and nicety must be exercised in their treatment, for the hydraulic classification of ores is an extremely delicate mechanical operation. While it 25 would be impossible to design a classifier of this character, which would be absolutely universal, still it is possible to do so within certain limits. Thus a classifier could be made to handle certain ores in a maximum 30 quantity carrying with it a certain amount of water and delivering specified spigot products. Adjustments could be incorporated in the machine that would allow 35 of the changing of the quantity of ore and water in varying proportions and also of the making of a different spigot product while at the same time the classifier would be doing its best work.

The object of my present invention is to provide a hydraulic classifier which will be adjustable to the greatest degree commensurate with the best results. Such a classifier must include a sorting column, a hydraulic 40 upward current, some sort of settling arrangement with means for eliminating rejected fines, any one of which elements is insufficient, but the proper combination of them all, each doing its proportion of work is what will produce the perfect apparatus. For instance, suppose some crushed ore be fed into a column 45 through which is passing a well regulated upward current of water, such particles as are of sufficient weight will fall through the current, while those too light will be held at the top of the column, but if the fines in suspension are not removed from their position directly over the column they will remain there only until a sufficient quantity or weight is accumulated and then drop in a body through the current which rejected them individually, but which lost its power 50 due to their accumulation. Thus, it will be seen that a most perfectly designed sorting column would not

perform the work expected of it unless combined with means for carrying away such fines as it would reject.

It is the purpose of the present invention to bring about these results in the most economical manner 60 possible and with the foregoing object in view, my present invention consists in certain novel features of construction and procedure which will be hereinafter described and pointed out in the claims.

In the accompanying drawings: Figure 1 is a view 65 partly in section through the classifier. Fig. 2 is an enlarged detail in section through the sorting column.

In Fig. 1 is shown a box or trough A which is made of sufficient width and depth to easily carry the feed and water which is introduced at A' and flows in the 70 direction indicated by the arrow. The inclination of the trough is to be such as to cause an easy flow that will freely carry the large particles along the bottom. The letter a is a fixed baffle board whose lower end extends down at least four inches into the pocket B. A 75 screen b preferably bridges over from the bottom of the trough to the baffle board a and the openings in this screen are at least five times the size of the largest particle being treated. The function of this screen b at this point is to slightly retard the finer particles in the 80 eddies formed directly beneath the wires so that the coarser particles settle while the fines are kept in agitation and suspension.

The letter c indicates a movable board which is adjustable by means of the toggles d, d, through the medium of the connecting rod e, bell crank e' and operating rod e''.

D, represents the sorting column fully set forth in my application filed November 26, 1906, Serial No. 345,179. This is bolted to the bottom of the pocket so 90 that it is directly beneath the opening C. The sorting column is shown in detail in Fig. 2. The numeral 1 is a flange by which the sorting column is bolted to the bottom of the pocket. A pipe 2 preferably screws into this flange 1 and extends downwardly; with it the 95 glass tube 4 is adjustably connected through the stuffing box 3. The glass part 4 of the sorting column is of proper diameter to slip into the pipe 2. A water chamber 6 has connected with it an outer tube 7 to which is connected a box 8 in which the lower end of the 100 glass part 4 is adjustable. The outer tube 7 is provided with perforations 9, which distribute the water in the annular opening between itself and the inner tube 10. The numeral 11 indicates the discharge pipe and 12 is a spigot. These lower parts are sustained by 105 means of rods 13, 13, which screw into the flange 1, while the nuts 14, 14, of these rods are adjustable to vary the length of the sorting column. The principal portion of the water issuing in the upward current is admitted through a gate valve 14' by means of a short 110 hose 15 to chamber 6 and another supply is possible through a mechanically operated gate valve 16 to the

same chamber. The object of the additional current is to create a pulsating effect the tendency of which is to disperse any accumulation in the top of the column. This gate valve 16 could be easily arranged to be mechanically operated to open at stated intervals, as for instance by the employment of an eccentric 19 on shaft 20 and a connecting rod 18 which extends from the eccentric to the stem 17 of the valve. It is understood of course, that any number of these sorting columns might be employed and by the medium of the rods and bell cranks c , c' , c'' , the operation in all would be alike as the several spaces C C could be changed to the proper size to dispose of the rejects from the sorting column.

15 In operation, the ore fed in at A' is carried by the water and the inclination of the trough to the first pocket where it easily passes the screen b , the meshes of which are of large dimensions. The tendency of the screen at this point is to slightly retard the finer particles in the eddies formed directly beneath the wires and thus the coarser particles settle while the fines are kept in agitation and suspension. The pulp passes under the fixed baffle board a and directly over the sorting column D. The hydraulic upward current should be absolutely uniform, and under instant and certain control and its mode of introduction one that will cause the least number of eddies and counter currents. Experiments have shown that an evenly rising current is better than a vortex when the length of sorting column is accurately proportioned. The vortex current contains and produces the objectionable eddies and counter currents. The hydraulic pressure, it will be assumed, has been regulated for the desired spigot product. The spigot has a constant opening. The elimination of eddies and counter currents in the column is accomplished by the peculiar combined arrangement of water chamber, and outer tube with the perforations, and the inner tube, which properly distributes the water. This causes a quiet upward current which allows the properly weighted particles to fall, while those too light are held without the tube. Perhaps the length of the sorting column is not correct for the product desired. A glance at the interior of the sorting column through the glass portion will quickly tell and its length can be adjusted by means of the slip joint shown at 3, Fig. 2. Should the fines be accumulating over the column in the pocket to the extent that they fall in the downward current, the glass portion of the column would show it, and an adjustment of the movable board c contracting the opening C will carry these fines to the next compartment.

When an ore having components with similar gravities, is being treated it might be well to have additional currents which would pulsate in effect and would tend to disperse the accumulation in the top of the column. This is easily provided for by the use of the gate valve O which can be mechanically operated to

open at stated intervals. It will be understood that the combination introduced in this classifier admits of thorough adjustment which will permit of variations 60 of feed without impairing its efficiency. The length of the sorting column is readily changed to accommodate conditions. The glass portion of the top allows interior inspection, which shows the exact action and may suggest any adjustment needed. This system 65 may be carried through any number of pockets, two only of which are illustrated. The final overflow should be impounded in a settling box. The discharge may be regulated to thicken. The settling arrangement may be of different forms, but it is required to 70 bring all ore particles in contact with the hydraulic current and simplicity of design with positive operation is the principle necessitated.

This classifier is especially adapted to a lead-zinc-iron classification as experiment has shown but it is evident 75 it could be applied to all classes of work.

It is evident that more or less slight changes might be resorted to in the form and arrangement of the several parts described without departing from the spirit and scope of my invention, and hence I do not wish 80 to limit myself to the exact construction herein set forth, but:—

Having fully described my invention, what I claim as new and desire to secure by Letters Patent, is:—

1. The combination with a trough having a pocket 85 therein, a fixed and a movable baffle board in said pocket and means for moving the movable baffle board bodily to one side.
2. The combination with a trough having a pocket 90 therein, a fixed and a movable baffle board in said pocket the latter movable bodily to one side, means for adjusting the movable baffle board, and a screen extending from one end of the pocket to the fixed baffle board.
3. The combination with a trough having a pocket 95 therein, a fixed and a movable baffle board in said pocket and means for adjusting the movable baffle board bodily to one side and a sorting column leading into the pocket.
4. The combination with a trough having a pocket 100 therein, a fixed and a movable baffle board in said pocket, means for adjusting the movable baffle board bodily to one side, and an adjustable sorting column leading into the pocket.
5. The combination with a trough having a pocket 105 therein, a fixed and a movable baffle board in said pocket, means for adjusting the movable baffle board bodily to one side, a sorting column leading into the pocket, and means for controlling the waterflow therein.
6. The combination with a trough having a pocket 110 therein, a fixed and a movable baffle board in said pocket, means for adjusting the movable baffle board bodily to one side, a sorting column leading into the pocket, means for controlling the water flow therein and means for creating a pulsating current in the water.

In testimony whereof I have signed my name to this specification in the presence of two subscribing witnesses. 115
